COMBINED ELECTRIC CAN OPENER AND KNIFE SHARPENER

Daniel E. McCue, Huntington Beach, Calif., assignor to
Rival Manufacturing Company, a corporation of
Missouri

Continuation of design applications Ser. No. 10,241 and
10,259, Jan. 22, 1968. This application July 23, 1968,
Ser. No. 13,480

Term of patent 14 years

Int. Cl. D8—02

U.S. Cl. D8—35

Fig. 8.

Fig. 9.

Fig. 10.

Fig. 11.

Fig. 12.

FIG. 1 is a rear perspective view of a combined electric can opener and knife sharpener showing my new new design;

FIG. 2 is a top plan view thereof;

FIG. 3 is a front elevational view thereof;

FIG. 4 is a side elevational view thereof taken from the right hand side of FIG. 3;

FIG. 5 is a rear elevational view thereof;

FIG. 6 is a side elevational view taken from the left hand side of FIG. 3;

FIG. 7 is a rear perspective view of a modified combined electric can opener and knife sharpener showing my new design;

FIG. 8 is a top plan view thereof;

FIG. 9 is a front elevational view thereof;

FIG. 10 is a side elevational view thereof taken from the right hand side of FIG. 9;

FIG. 11 is a rear elevational view thereof; and

FIG. 12 is a side elevational view taken from the left hand side of FIG. 9.

The dominant features of the design reside in the portions shown in full lines.

This is a continuation of design applications Ser. Nos. 10,241 and 10,259 both filed Jan. 22, 1968, and both now abandoned.

I claim:

The ornamental design for a combined electric can opener and knife sharpener, as shown and described.
